UNITED STATES PATENT OFFICE.

WILHELM JAHNS, OF OFFENBACH-ON-THE-MAIN, GERMANY.

CENTRIFUGAL GOVERNOR.

1,116,707.

Specification of Letters Patent. Patented Nov. 10, 1914.

Application filed April 9, 1913. Serial No. 760,023.

To all whom it may concern:

Be it known that I, WILHELM JAHNS, a subject of the German Emperor, and resident of Offenbach-on-the-Main, Germany, 5 have invented certain new and useful Improvements in Centrifugal Governors, of which the following is a specification.

This invention relates to an improvement in such centrifugal governors for power engines in which the centrifugal forces set up 10 in the centrifugal masses by the rotation are directly received by springs. The well known governors of this kind are not provided with a positive parallel guiding of 15 their centrifugal masses so that these centrifugal masses which are suspended so as to be able to rotate around their centers of gravity are allowed within certain limits to assume arbitrary positions and in fact do 20 assume such positions. In general, the governor springs in the constructions known until now are used or considered as auxiliary means for ascertaining the parallel guiding of the centrifugal masses. But as these 25 springs always are compression springs, the parallel guiding ascertained by same is a very questionable one as not only little inexactitudes in the construction of the springs (especially of their extreme flat surfaces) or 30 of the centrifugal masses but also the unavoidable friction between the centrifugal masses and their pivots, branches or supports so to speak compulsorily produce a lateral flexing of the springs and consequently 35 a corresponding oblique position of the centrifugal masses. Besides, the vibrations which are absolutely unavoidable during the working of such a regulator as well as possible reactional pressures originating 40 from the valve gear are able to cause the centrifugal masses to assume an oblique position and to cant with their centers of relation.

Figures 3, 4 and 5 show such constructions 45 in which the centrifugal masses are rotatably suspended from their centers of gravity and are compelled solely by the springs to move approximately parallelly to themselves.

50 In the construction shown by Figs. 1 and 2, the centrifugal masses are not mounted

on one single axis passing through their centers of gravity; but two axes *c* and *c'*—*c'* are provided at a considerable distance from the center of gravity, of which axes the 55 one *c* is guided through the medium of a single roller on the guide way *d* and the axes *c'*—*c'* through the medium of two rollers on the guide-ways *d'*—*d'*. In this system of guiding the centrifugal masses the own 60 weight of the latter always acts in such a manner that the centrifugal masses are shifted in parallel relation to themselves. A canting of the centrifugal masses around their center of suspension as this is possible 65 in the constructions shown by Figs. 3, 4 and 5 is impossible *a priori* in the constructions shown by Figs. 1 and 2, as will be readily understood; but in the latter constructions it may happen that the centrifugal 70 masses are lifted from one of their guide-ways through vibrations, etc., or, in marine engines, as a consequence of the oscillations of the vessel as long as shocks are produced between the centrifugal masses *a* 75 and their rollers *c*, *c'*—*c'* and the guide ways *d*, *d'*—*d'*.

Now, this invention relates to a device by which the centrifugal masses of the governors of the kind considered here are positively guided or held in such a manner that they are always compelled to move in all circumstances parallelly to themselves and are also prevented from being lifted from their guide-ways by vibrations, etc. 85

The accompanying drawing shows several forms of embodiment of the principle of the invention applied to various types of governors.

In the form of embodiment shown by 90 Figs. 1 and 2, the improvement has been shown as applied to a governor system in which the centrifugal masses *a* which are acted upon by the springs *b* are guided on the guide ways *d*, *d'*—*d'* positioned in a 95 horizontal plane by means of a system comprising three supporting rollers *c*, *c'*—*c'*. This kind of guiding had for the centrifugal masses *a* this advantage that they were exactly guided in the horizontal plane. In 100 this arrangement, too, the centrifugal masses, would be held under normal con-

ditions in their correct position *i.e.*, would move parallelly to each other as their center of gravity was lying inside the three points of support. On the contrary it was possible 5 for the centrifugal masses to be lifted from the corresponding guide-way both as a whole and by any one of their supporting rollers $c, c' - c'$. In order to remedy this drawback, a double armed lever e has been provided above the centrifugal masses a which 10 lever carries at each end a roller f . This lever is adjusted by means of the nut g on the shaft p in such a manner that it holds in a lasting manner the centrifugal masses 15 a uniformly on their guide-ways $d, d' - d'$ and this, it is needless to say, without hindering their radial motion. By this arrangement it is obtained that the centrifugal masses never cant toward one side, nor can 20 rise bodily from their rolling surfaces whatever may be the causes tending to bring about such a non-intentioned and unfavorable motion.

In the second form of embodiment the 25 principle of the invention is applied to a governor construction in which, as shown by Figs. 3 and 4 the centrifugal masses a , are guided in slot like guides $i - i$ by means of a coaxial system of rollers $h - h$ positioned 30 in the center of gravity of the centrifugal masses. In this construction it is true, an important vertical motion is prevented by these guides, but on the other hand the centrifugal masses can turn around the 35 rollers $h - h$ or the pivots thereof; as readily seen the centrifugal bodies are not compelled to move during their radial movements parallelly to themselves and, besides, they will be able to vibrate, in certain cases between the guide-planes $i - i$ whereby an objectionable stress is put upon the guide-planes 40 themselves as well as upon the guide-rollers, etc. Both drawbacks are avoided by the provision of the lever e ; but in this case the latter is provided besides the rollers f at its 45 free ends with an additional roller f' on each arm. Owing to the fact that these rollers f and f' are at a certain distance from each other and are arranged in such a manner 50 that in all the positions of the centrifugal masses they are positioned on both sides of the guide rollers $h - h$ which are positioned in the centers of gravity of the masses, it is impossible that the centrifugal masses 55 cant during their motions and that they can perform any upward motion whatever. As readily seen one may in this case, if desired, build the slot guides $h - h$ as simple straight surfaces.

60 Figs. 5 and 6 finally show the application of the principle of the invention to a type of governor in which the centrifugal masses are guided by means of systems of links, Fig. 5 showing diagrammatically the employment 65 of one pair of links and Fig. 6 the em-

ployment of two pairs of links for each centrifugal mass. In the first named construction (Fig. 3) we again find essentially the double lever e having two guide rollers f and f' on each arm which has already been seen in the second construction (Figs. 3 and 4). But as in this case the centrifugal masses a do not perform a rectilinear radial motion but move along an arc of a circle having for its center the point of support k 75 of the link l , it is necessary to provide means allowing the double armed lever e to follow this movement. To this end it is guided on the extension m of the shaft p so as to be able to move up and down thereon and it is 80 pressed downward by a spring n in such a manner that the effect aimed at by the present invention is fully attained.

In the governor construction shown by Fig. 6 in which the centrifugal masses a are each guided on two pairs of links, the lever 85 e having only one roller at each end will again be sufficient; but the spring arrangement used in the form of embodiment just described is also necessary in this case.

The inventor wishes it to be expressly understood that it is not his intention to restrict the field of application of the device forming the subject matter of this invention; to the arrangements shown by way of example in the drawing. Thus for instance it is not necessary that the geometrical axes $x - o$ and $o - y$ of the two centrifugal masses be on the same straight line; they can also be inclined under a certain angle with reference to the horizontal plane as this has been shown diagrammatically by Fig. 7. Besides it is not at all necessary that the two armed lever e be arranged "above" the centrifugal bodies; on the contrary the same 105 can be positioned on both sides of the centrifugal masses at any desired height of same with the same technical effect. Furthermore, it is not absolutely necessary that the two armed lever be directly connected with the 110 shaft p ; it can also be arranged on the casing q or on any other structural part connected with the shaft p .

Having now fully described my said invention, what I do claim and desire to secure 115 by Letters Patent, is:

1. In a centrifugal governor of the kind described, the combination with a plurality of centrifugal masses, of guides located below said masses and fixed in relation thereto, and an adjustable guide above said masses.
2. In a centrifugal governor of the kind described, the combination with a plurality of centrifugal masses, of guides located below said masses and fixed in relation thereto, and an adjustable guide above said masses, said adjustable guide being provided with spaced guide rollers for each of said masses.
3. In a centrifugal governor, the combina- 130

tion of a governor shaft; a plurality of arms radiating from said shaft, a bar mounted on said shaft and extending above said arms, centrifugal masses mounted on said arms and 5 slideable longitudinally thereof, guides on said bar engaging said masses, a spring surrounding said shaft and urging said bar toward said masses, and a linkage connected to said masses and adapted for connection to a valve controlling sleeve on said shaft. 10

In testimony whereof I have hereunto set my hand in presence of two witnesses.

WILHELM JAHNS.
